PAPER RECEPTACLE AND PROCESS OF
MAKING SAME

George W. Poppe, Brooklyn, N. Y., assignor to
Equitable Paper Bag Co. Inc., Brooklyn, N. Y.,
a corporation of New York

Application June 26, 1934, Serial No. 732,494

2 Claims. (Cl. 206—46)

This invention relates to paper receptacles and more particularly those receptacles designed for holding merchandise or for mailing matter which requires inspection by the postal authorities.

5 An object of the invention is the production of an article of this sort which can be made rapidly and inexpensively.

Another object is the production of an article which is adapted for use in mailing second class 10 matter such as magazines and the like whereby the matter is securely held within the receptacle but may be readily inspected.

15 A feature of the invention resides in the formation of flaps at the top of an ordinary bag having a reenforced bottom, which flaps are adapted to be folded inside the receptacle, each along a single line of fold.

20 Another feature or object of the invention resides in the provision of tapered flaps at the open end of the bag, which shape enables them to be folded inside the receptacle and to be rapidly inserted between the leaves of a magazine, for instance, to thereby securely hold the same within the receptacle thus rendering unnecessary the employment of special closure devices and at the 25 same time permitting ready inspection of the contents without withdrawing the flaps.

25 Further features and advantages will become apparent from the following description and 30 claims when taken in connection with the accompanying drawings in which:—

Figure 1 is a perspective view of my improved receptacle ready for use;

Figure 2 is a longitudinal sectional view 35 through the receptacle, showing how the flaps are folded and inserted between the pages of a magazine contained within the receptacle;

Figure 3 is a front elevation of the upper portion 40 of the receptacle with parts broken away to show how the trapezoidal flaps enable the same to be inserted within the pages of a magazine;

Figures 4 and 5 are views showing some of the steps in the process of making my improved receptacle and

45 Figure 6 is a longitudinal section through a bag machine showing how the article is produced on such a machine.

Referring to Figures 1 and 2, the article forming the subject matter of the present application 50 comprises a front wall 2 and a seam wall 3. A closing flap 4 which is a prolongation of the wall 2 is folded over onto the seam wall and pasted thereto. The seam is shown at 5. The top of the bag is formed into two flaps 6 and 8. These may 55 be rectilinear in shape but preferably they are

trapezoidal. Each flap is adapted to be folded along the score line 10 and inserted in the receptacle. A notch 12 formed in the flap 6 enables ready separation of the flaps. In Figure 2 a magazine or similar article 13 is shown inside the receptacle and the flaps 6 and 8 are shown folded over and inserted between the leaves of the magazine, thereby securely holding it within the receptacle but nevertheless permitting ready inspection of the same.

5 The purpose of making the flaps 6 and 8 of tapered or trapezoidal shape is more clearly indicated in Figure 3 where the fastening devices 14 of the magazine are shown. The flaps thus shaped lend themselves to ready insertion between the leaves of the magazine and also makes it more convenient to fold them inside the bag than if they were rectilinear in shape.

10 It is not essential that the flaps 6 and 8 be of equal length but they should be of such length 20 and so proportioned to the size of the magazine, booklet or similar article that they may be interleaved with the leaves of such article.

15 The method of making the receptacle is illustrated in Figures 4, 5 and 6. Referring to Figure 5, 25

a web of paper 16 to which a line of paste 17 has been applied is folded to form a bag tube, which tube is severed into bag lengths in a manner well known in the art of bag making. Preferably this folding, pasting and severing is done 30

on an ordinary bag machine and in Figure 6 I have shown more or less diagrammatically a cross-section of such machine with the necessary additions and modifications which fit it to carry 35 out the preliminary steps in the making of my improved receptacle. Referring to this figure, the web 16 is fed from a roll of paper 18, which web, after passing suitable guiding rollers, is fed to the reversing roller 20, at which point the line of

paste 17 is applied by a paste disc 22 revolving 40 in a paste pot 23. From the roller 20 the web passes under the heel of a former 24 and is drawn along by the usual feed rollers 26. The

edge of the former is serrated at 28 and there is the usual lip knife 30 also having a serrated edge. After passing the feed rollers, the bag tube is 45 led between the usual pinch bars 32 which momentarily retard it at the same instant a striker

bar 34, carried by a sprocket chain 35, delivers a sharp blow to the tube from beneath. After a bag section is severed from the tube and at the instant the pinch bars free it, the severed bag

section is pulled forwardly by scoring devices 36, which devices make the score line 10. The bag 50 55

then passes to the usual cylinders 38 which fold and paste the bottom.

The upper cylinder is provided with the usual paste bar 39 which receives paste from a roller 40 rotating the paste supply vessel 41, all of these parts being of the usual construction and found in an ordinary bag machine. The lower cylinder 38 carries the usual clamp 42 with which cooperates the tucker blade 43 by which the bag bottom is folded. The finished bag then passes to the usual delivery mechanism indicated generally by 44.

When the web is passing over the roller 20 a die 46 carried by the shaft 47 suitably driven from the lower pinch bar shaft 33 makes an incision in the web, said incision eventually forming the notch 12, Figures 1 and 2. The incision is also indicated as 12 in Figure 5. The bag, after being severed by the striker bar 34 and before the bottom is folded by the cylinders 38 has the appearance depicted at the left, Figure 5. It will be noted that the lower serrated edge 48 of the seam wall is offset from the lower wall so that when the tube section is folded along the line 25 *a—a*, Figure 5, a portion of the seam wall is included within the fold. This gives a reenforced bottom which is peculiar to a bag as distinguished from an envelope. The line of paste applied by the bar 39 is indicated at 49, Figure 5.

It is to be understood, of course, that the timing of the various parts of the machine is such that the score line 10 is made at the proper place.

After the bag tube section has passed the cylinders 38, it has the appearance shown in Figure 4.

In order, however, to produce the bag shown in Figure 1, further operations are necessary. These consist in cutting the bag tube transversely along a line *b—b* which is within the serrations 40 50, Figure 4. This operation may be performed with an ordinary paper cutter. The edges of the bag are also cut along the lines *c—c* and after this cutting operation the bag presents the appearance shown in Figure 1. The angle at which

the cuts *c—c* are made may, of course, be varied as desired.

Where the two flaps 6 and 8 are of equal length then it is convenient to provide the notch 12 in one of these flaps for convenience in opening the bag mouth. The incisions which create these notches, each of which is made by the die 46, are at bag length intervals apart and the timing may be such that when the tube is severed along the line 50, Figure 5, such line of severance will be just above the ends of the incision. This position of the incision prevents a tab appearing at the end of the flap of the finished bag. While this necessitates a trifle more waste of paper when the bag is cut off along the line *b—b*, Figure 4, 15 the finished bag has a better appearance.

When the flaps are not required to be of equal length, the cuts along the line *b—b* may be dispensed with, only the cuts *c—c* being made.

From the foregoing it will be seen that I have produced a bag which is admirably adapted for the use for which it is intended but which may be manufactured at low cost.

What is claimed is:—

1. An inspectable mailing package comprising a receptacle of flexible material containing a magazine, booklet or the like with one of the free edges thereof facing the mouth of the receptacle, the two edges of the mouth each having a flap extending inwardly and interleaved within the leaves of the magazine, booklet or the like, the relative size of the receptacle as compared with the contents being such that the distance between the ends of the inturned flaps and the bottom of the receptacle is less than the corresponding dimension of the magazine, booklet or the like.

2. As an element of the combination set forth in claim 1, a receptacle of flexible material having each edge of its mouth provided with a tapered flap, said flaps being proportioned and dimensioned to interleave and interlock with the contents of the receptacle.

GEORGE W. POPPE.
